UNITED STATES PATENT OFFICE

124,811

DESIGN FOR A UNIT HEATER

Donald P. Wilson, St. Louis Park, Minn., assignor
to McQuay, Inc., a corporation of Minnesota

Application October 12, 1940, Serial No. 95,787

Term of patent 7 years

To all whom it may concern:

Be it known that I, Donald P. Wilson, a citizen
of the United States, residing at St. Louis Park,
in the county of Hennepin and State of Minnesota,
have invented a new, original, and ornamental
Design for a Unit Heater, of which the
following is a specification, reference being had to
the accompanying drawing, forming part thereof.

Figs. 1 and 2 of the drawing are perspective

views of a unit heater, showing my new design,
Fig. 1 being a view taken from the top and one
side of the illustrated device and Fig. 2 being a
view taken from the bottom and the opposite side
of said device.

I claim:

The ornamental design for a unit heater, as
shown.

DONALD P. WILSON.
